SWITCH MECHANISM

Howard W. Ecker, St. Paul, Minn.

Application June 25, 1949, Serial No. 101,400

20 Claims. (Cl. 200—153)

1

My invention relates to switch mechanisms and particularly to a switch mechanism whereby a single mechanism may be readily converted into a normally open spring returned switch, a single stroke make and break switch or a normally closed spring returned switch. The object of the invention resides in providing a switch mechanism constructed as herein disclosed and having the mode of operation, functions and advantages set forth.

The switch mechanism disclosed in this application for patent consists of a support and a rocking contact closer pivoted for movement about a shaft carried by the support and movable from a contact closing position to a contact opening position. Also mounted on said shaft is a selector having a spring mounting between which and the contact closer a spring is disposed and which exerts pressure in the direction of the shaft. The selector may be positioned to cause the spring to be on dead center with respect to the axis of the shaft when the contact closer is in an intermediate position or said selector may be positioned to cause said spring to urge the contact closer into either its contact closing or its contact opening position regardless of the position of the contact closer. Positioning means operating in conjunction with the selector serves to hold the selector in any of said positions. The contact closer is moved from one position to the other by means of an actuator which is pivoted relative to the contact closer and which is adapted to be actuated by means of a manual or other operating member carried by the support. This actuator is adapted to be moved into two positions and upon actuation when in one position moves the contact closer to contact closing position and when in its other position upon actuation moves the contact closer to contact opening position. Two opposed springs act on the said actuator and urge the same to an intermediate position. One or the other of these springs is adapted to be rendered ineffective by a lug movable with the selector. This lug is so positioned that when the selector is in its intermediate position both springs are effective to permit of the switch functioning as a single stroke make and break switch and when the selector is in one of its extreme positions and the first named spring is in position urging the contact closer into contact closing position the spring of the two springs tending to move the actuator into contact opening position is ineffective thereby making of the mechanism a normally closed spring returned switch. The said lug is likewise so constructed and positioned that when

2

the first named spring is in position, urging the contact closer into contact opening position the other spring of the two springs tending to move the actuator into contact closing position is likewise ineffective thus making of the mechanism a normally open spring returned switch.

In the drawings:

Fig. 1 is a plan view of a switch mechanism illustrating an embodiment of my invention with parts cut away to show the construction of the switch mechanism.

Fig. 2 is a sectional view taken on line 2—2 of Fig. 1.

Fig. 3 is a cross sectional view taken on line 3—3 of Fig. 2 and drawn to a greater scale, the parts being arranged for normally closed operation of the switch.

Fig. 4 is a cross sectional view similar to Fig. 3 and showing the switch in open position.

Fig. 5 is a cross sectional view taken on line 5—5 of Fig. 2 and showing the parts arranged as in Fig. 3.

Fig. 6 is a view similar to Fig. 5 showing the parts as arranged in Fig. 4.

Fig. 7 is a cross sectional view similar to Fig. 3 and showing the parts arranged for single stroke make and break action and illustrating the switch in closed position.

Fig. 8 is a view similar to Fig. 7 showing the arrangement of parts after the switch mechanism has been depressed.

Fig. 9 is a view similar to Fig. 8 showing the parts after the switch mechanism has been released and illustrating the switch in open position.

Fig. 10 is a view similar to Fig. 8 showing the switch mechanism as having been depressed from the position illustrated in Fig. 9.

Fig. 11 is a view similar to Fig. 3 showing the parts arranged for normally open, spring returned action and showing the switch open.

Fig. 12 is a view similar to Fig. 11 showing the switch closed.

Fig. 13 is a fragmentary elevational sectional view taken on line 13—13 of Fig. 1.

The invention disclosed in this application comprises a flat case 10 having side walls 11 and 12, a rear wall 13 and a sloping front wall 14. The wall 14 merges with a top 15 which is also connected to the other walls. The case is open at the bottom and is preferably constructed of cast iron or some other suitable metal giving to the entire device sufficient weight. Overlying the front wall 14 and top 15 is a sheet 16 of friction material by means of which the case may be

stepped on and the user's foot prevented from slipping off the case. The case 10 is formed with a rabbet 17 which extends completely about the case.

The invention further comprises a base 18 which is constructed from sheet metal and which is attached to and overlies a sub base 19. Between the base 18 and sub base 19 is a sheet of rubber 21. These various parts are secured together by means of rivets 22. The sub base 19 and the sheet of rubber 21 are received within the rabbet 17 and are attached to the case 10 by means of screws 23 which are counter sunk in the sub base 19 and are threaded into the wall structure of the case 10.

Mounted on the base 18 is a switch 24 which may be of any suitable construction and which is provided with two terminals 25 and 26. This switch has an operating button 27 extending outwardly through the case 28 thereof and which is adapted to close the contacts of the switch and complete the circuit through terminals 25 and 26 when the said button is forced inwardly into the switch. The button 27 and the contacts of the switch are spring returned so that the switch is normally open and may be closed by pressure on the button 27 and upon release of pressure returns to normally open position. Inasmuch as switches of the type illustrated are well known in the art and since the particular construction of the switch forms no feature of the instant invention the switch has not been shown in detail and will not be described.

The invention utilizes an operating member 30, best shown in Fig. 1. This member is constructed from wire U-shaped in form having spaced arms 31 and 32 and an elongated cross member 34. Inwardly facing trunnions 35 are formed on the ends of the arms 31 and 32 which are rotatably received in bearings 36 extending upwardly from the base 18. These trunnions and bearings form guide means for guiding the cross member 34 for up and down movement. The operating member 30 is normally forced downwardly against the sheet of rubber 21 by means of a leaf spring 37. This leaf spring overlies the cross bar 34 and is disposed between the sheet of rubber 21 and the base 18 and is held in place by means of the rivets 22. The operating member 30 is operated by means of a pad 38 of any suitable material such as rubber which is cemented to the sheet 21 or formed integral therewith as desired. The pad of rubber 38 projects through an opening 39 in the sub base 19 and extends appreciably below the lowermost surface of the said sub base. Another pad of rubber 41 is attached to the sub base 19 at the end thereof nearest the wall 13 of case 10. When the switch mechanism is placed upon the floor the same rests on the pads 41 and 38, the sub base 19 being elevated above the floor. When pressure is applied by the foot of the user to the sheet 16 of friction material the entire case 10 is depressed and the pad 38 forced inwardly into the compartment 42 formed within the case 10. The sheet of rubber 21 by engagement with the cross bar 34 urges the said operating member 30 upwardly against the action of the spring 37 until it occupies a position such as shown in Fig. 4.

For operating the button 27 of switch 24 and closing the contacts of said switch a contact closer 43 is employed. This contact closer is U-shaped in form having spaced legs 44 and 45 with a connecting portion 46 therebetween. A

shaft 47 extends through the said legs 44 and 45 and through bearings 48 and 49 bent upwardly from the base 18 and forms therewith pivot means for said contact closer. The shaft 47 is disposed near the base 18 and appreciably below the button 27. Formed on the contact closer 43 is an arm 51 which issues outwardly from the leg 45. This arm is of appreciable lateral extent and at the uppermost portion of the same is adapted to engage the button 27. When the contact closer 43 is moved in a counter clockwise direction as viewed in Fig. 3 arm 51 forces the button 27 inwardly and closes switch 24. When the contact closer 43 is moved in the opposite direction the arm 51 leaves the button 27 and permits the spring within the switch 24 to open the contacts of said switch. Movement of the contact closer into contact closing position is terminated by the structure with which the button 27 reacts and serves as a stop. Movement of said contact closer into contact opening position is terminated by another stop formed by the base 18 which engages a corner 84 of the leg 44 of contact closer 43.

For the purpose of shifting the contact closer 43 to its various positions an actuator 52 is employed. This actuator is constructed from wire and has a shaft-like portion constructed in two sections 53 and 54. The shaft section 54 is journaled in a bearing formed in the leg 45 of contact closer 43 while the section 53 is similarly journaled in a bearing formed in the leg 44 of said contact closer. This construction provides pivot means for the actuator. The shaft section 54 is formed with an offset 55 which projects upwardly therefrom. The shaft section 53 is bent downwardly as designated at 56 and is formed at its lower end with a foot 57 adapted to engage the cross bar 34 of operating member 30. The foot 57 travels in a slot 58 in the leg 44 of contact closer 43 the portions of said leg at the ends of said slot serving as stops for limiting the movement of the actuator with reference to the said contact closer. The actuator 43 is normally held in an intermediate position by means of a hairpin spring 59 which has two reaches or spring members 61 and 62. These reaches straddle the offset 55 and both operate to move the actuator toward an intermediate position.

Operating in conjunction with the contact closer 43 is a selector 63. This selector is constructed from sheet metal and is U-shaped in form having spaced parallel flanges 64 and 65 and a web 66 connected therewith. The shaft 55 47 extends through the flanges 64 and 65 and which serve as guide means for guiding the said selector for swinging movement about the axis of said shaft. A compression coil spring 67 encircles the shaft 47 and is seated at one end against the bearing 48 and its other end against the flange 64 and urges the flange 65 toward the leg 45 of the contact closer 43. Acting between the selector 63 and the contact closer 43 is a spring 68, as shown in Fig. 1. This spring has a loop 69 with two arms 71 and 72 extending outwardly therefrom. The arm 71 is hooked into the opening 73 formed in the leg 44 of contact closer 43 while the arm 72 passes through openings 74 in the flanges 64 and 65 of the selector 63. The openings 73 and 74 are so located that when the selector 63 is in the position shown in Figs. 3, 4, 5 and 6 the spring 68 urges the contact closer 43 into contact closing position. When the selector 63 is in the position shown in Figs. 11 and 12 the said spring

urges the contact closer into contact opening position regardless of the position of said closer. When, however, the selector 63 is in the position shown in Figs. 7 to 10 the spring 68 may urge the contact closer into either opening or closing position depending upon the original position of said contact closer.

The selector 63 has a latch 75 formed on the web 66 thereof and which projects outwardly therefrom. This latch is adapted to cooperate with a positioning device indicated at 76. This device is formed by bending up a flange 77 from the base 18 and which extends parallel to the shaft 47. The said flange has in the end of the same three notches 78, 79 and 80 and into which the latch 75 may project. The spring 67 is adapted to urge the selector 63 toward the positioning device 76 to cause latch 75 to engage any of these notches and when disposed in said notches serves as locking means for holding the selector positioned in one of the three positions noted in Figs. 3, 7 and 11.

The flange 65 of the selector 63 has formed in the same a groove 82 through which the reaches 61 and 62 of spring 59 project and in which the said reaches may travel. In this groove is formed a lug 83 which is straddled by the said reaches. When the selector is in the position shown in Fig. 3 lug 83 engages the reach 62 and moves the same away from the offset portion 55 of actuator 52 and transfers control of said actuator to the reach 61 of said spring. When the selector is in the position shown in Figs. 7 to 9 the actuator may be operated by either spring. When the selector is in the position shown in Figs. 11 and 12 control of the actuator is transferred to the reach 62 of the same.

My invention operates in the following manner: Assume that the selector 63 is arranged as shown in Figs. 3, 4, 5 and 6 and that the switch mechanism is in normal position as shown in Fig. 3. In this position latch 75 is in notch 80 of positioning device 76. It will be noted that the lug 83 of selector 63 has moved the reach 62 of spring 59 away from the actuator 52. Reach 61 engages the offset 55 of said actuator and moves it toward the lefthand end of slot 58 as viewed in Fig. 3. The flange 64 of the selector 63 being lowermost spring 68 is so disposed that it urges the contact closer 43 in a counter clockwise direction bringing the arm 51 of said contact closer into engagement with the button 27 and closing the switch 24. The switch is now normally in closed position. If pressure is applied to the pad 38 by stepping on the case 10, the said pad moves inwardly into the compartment 42 and raises the cross bar 34 of the operating member 30. This causes the contact closer 43 to move in a clockwise direction and to swing the arm 51 out of engagement with the button 27 through the spring in switch 24. The switch 24 now opens. The various positions of the arm 51 with reference to button 27 are best shown in Figs. 5 and 6. Inasmuch as the opening 73 in the position shown in Fig. 4 is still above the line connecting the opening 74 and the axis of the shaft 47, the said spring still tends to urge the contact closer for movement in a counter clockwise direction. Upon release of pressure on the case 10 the parts through the action of the spring 68 return to normal position.

When the selector 63 is moved to the position shown in Figs. 11 and 12 with latch 75 disposed in slot 78 of the positioning device 76, the lug 83 engages the reach 61 of spring 59 and shifts

the same out of engagement with the offset 55 of actuator 52. The opening 73 in leg 44 of contact closer 43 is now below a line connecting the opening 74 in the flange 64 of selector 63 and the axis of shaft 47. This urges the contact closer 43 for movement in a clockwise direction, the said movement being limited when the corner 84 of the leg 44 of said contact closer engages the base 18. Reach 61 of spring 59 being now ineffective the reach 62 forces the actuator 52 for movement in a counter clockwise direction bringing the foot 57 of said actuator toward the righthand end of the slot 58. The switch 24 is thus maintained in normally open position. When the case 10 is again stepped on pad 38 is forced inwardly and the actuator 52 moves the contact closer 43 in a counter clockwise direction. This closes the switch 24. Upon release of pressure on the case 10 the parts are returned to normal position by means of spring 68 and the spring in the switch 24 opens the contacts of the switch.

When the selector 63 is moved to its intermediate position by directing the latch 75 into notch 79 the parts become arranged as shown in Fig. 7. Lug 83 in this case shifts the reach 62 of spring 59 out of engagement with the offset 55 of actuator 52. The opening 73 in leg 44 of contact closer 43 is slightly above a line connecting the opening 74 of flange 64 and the axis of shaft 47. The spring 68 hence urges the contact closer 43 for movement in counter clockwise direction and closes switch 24. When the case 10 is stepped on pad 38 is moved inwardly into the compartment 42 and the cross bar 34 of the operating member 30 is raised. This cross bar engaging the foot 57 of actuator 52 swings the contact closer 43 in a clockwise direction. Opening 73 is now disposed at a locality below the said line and the spring 68 urges the contact closer for clockwise movement and maintains it in the position shown in Fig. 8. At the same time the reach 62 of spring 59 has been forced to the right as shown in Fig. 8. Upon removal of pressure on the case 10 the reach 62 of spring 59 moves the actuator 52 with reference to the contact closer 43 so that the foot 57 of said contact closer reaches the righthand end of the slot 58 as shown in Fig. 9. A second depression of the case 10 swings the contact closer 43 to the left and shifts the parts to the position shown in Fig. 10. This closes switch 24 and spring 68 maintains the switch in closing position. Upon release of pressure on the case 10 actuator 52 is forced by means of the reach 61 back into the position shown in Fig. 7. It will thus be seen that with the parts disposed as illustrated in Figs. 7 to 10 that a single stroke, namely pressure on the case 10, will cause the switch to be alternately opened and closed.

The advantages of my invention are manifest. My improved switch construction can be readily adjusted to procure a normally opened spring returned switch, a single stroke make and break switch, or a normally closed spring returned switch. The invention can be constructed at an economical expense. My switch mechanism is particularly adapted to be used for foot operation. With my switch mechanism the entire switch may be enclosed thereby preventing dirt and foreign material from entering the same. In my switch mechanism fire hazard is reduced to a minimum and no possibility of shock exists.

Changes in the specific form of my invention, as herein described, may be made within the scope

of what is claimed without departing from the spirit of my invention.

Having described my invention, what I claim as new and desire to protect by Letters Patent is:

1. In a switch mechanism, a support, an operating member, guide means acting between said support and operating member for guiding said operating member for movement in a certain direction, a rocking contact closer, pivot means acting between said support and contact closer and guiding said contact closer for rocking movement about an axis transverse to the direction of movement of said operating member, said axis lying in a plane parallel to the direction of movement of said operating member, stops between said contact closer and support and limiting movement of said contact closer to contact closing and opening positions, an actuator for said contact closer carried thereby, pivot means for said actuator guiding said actuator for swinging movement about an axis parallel to the axis of the pivot means for the contact closer and disposed on one side of said axis, the axis of said actuator being movable from one side to the other of said plane upon movement of the contact closer from contact opening to contact closing position, an engaging member on said actuator engageable with said operating member and adapted to be moved to either side of said plane upon swinging of said actuator, stops between said contact closer and actuator and limiting movement of said actuator to positions in which said engaging member engages the operating member on either side of said plane, said operating member when both said engaging member and the axis of said actuator are on one side of said plane urging rocking movement of the contact closer in a direction to shift said axis to the other side of said plane, resilient means for urging said engaging member to the same side of said plane as the axis of the pivot means for said actuator comes to rest in and resilient means for urging said contact closer to one or the other of its positions.

2. A switch structure as recited in claim 1 in which the last named resilient means is shiftable to cause said contact closer to recurring return to either contact closing or contact opening position.

3. A switch structure as recited in claim 1 in which the last named resilient means is mounted for over center action to alternately urge said contact closer into opposite positions.

4. A switch structure as recited in claim 1 in which a spring mounting is employed together with pivot means therefor having its axis coaxial with respect to the axis of the pivot means for the contact closer and pivotally supporting the last named resilient means for engagement with the contact closer at a locality shiftable into alignment with the axis of the pivot means for the contact closer and for the resilient means with respect to said mounting or to either side of its position of alignment.

5. In a switch mechanism, a base, an operating lever pivoted to said base and having vertical movement, a rocking contact closer, a shaft for pivoting said contact closer for rocking movement relative to said base, the axis of said shaft being substantially horizontal, stops between said contact closer and base limiting movement of said contact closer to contact closing and opening positions, an actuator for said contact closer comprising a shaft rotatably mounted with respect to the contact closer, the axis of said shaft being parallel to the axis of said first named shaft

and disposed above said first named shaft, said second named shaft being positioned to be moved from one side to the other of a vertical plane passing through the axis of said first named shaft, an engaging arm on said actuator disposed below said first named shaft and adapted to be engaged by said lever, resilient means acting between said actuator and contact closer and controlling the relative position of said actuator with respect to said contact closer, and other resilient means acting between said contact closer and a part carried by said base and controlling the disposition of said contact closer with reference to said plane.

6. In a switch mechanism, a base, an operating lever pivoted to said base and having vertical movement, a rocking contact closer, a shaft for pivoting said contact closer for rocking movement relative to said base, the axis of said shaft being substantially horizontal, stops between said contact closer and base limiting movement of said contact closer to contact closing and opening positions, an actuator for said contact closer comprising a shaft rotatably mounted with respect to the contact closer, the axis of said shaft being parallel to the axis of said first named shaft and disposed above said first named shaft, said second named shaft being positioned to be moved from one side to the other of a vertical plane passing through the axis of said first named shaft, an engaging arm on said actuator disposed below said first named shaft and adapted to be engaged by said lever, resilient means acting between said actuator and contact closer and controlling the relative position of said actuator with respect to said contact closer, and other resilient means acting between said contact closer and a part carried by said base and controlling the disposition of said contact closer with reference to said plane.

7. In a switch mechanism, a contact closer movable from contact closing to contact opening position, a spring for urging movement of said contact closer, and a selector for shifting said spring to urge movement of said contact closer into one or the other of said positions.

8. In a switch mechanism, a contact closer, pivot means therefor, stop means for limiting movement of said contact closer to contact closing and opening positions, a spring mounting, a spring carried thereby and engaging said contact closer outwardly of the axis thereof, guide means for guiding the portion of said mounting engaged by the spring in a circumferential direction and positioning means for holding said spring mounting in a central position in which force is exerted on said contact closer by the spring in a radial direction when the contact closer is in an intermediate position, and for holding said spring mounting in extreme positions in which the contact closer is urged into either contact closing or opening positions regardless of the position of said contact closer.

9. In a switch mechanism, a contact closer, pivot means therefor, stop means for limiting movement of said contact closer to contact closing and opening positions, a spring mounting, a spring carried thereby and engaging said contact closer outwardly of the axis thereof, pivot means for said mounting having its axis coaxial with respect to the axis of said contact closer and positioning means for holding said spring

mounting in a central position in which force is exerted on said contact closer by the spring in a radial direction when the contact closer is in an intermediate position, and for holding said spring mounting in extreme positions in which the contact closer is urged into either contact closing or opening positions regardless of the position of said contact closer.

10. In a switch mechanism, a support, a rocking contact closer, a shaft carried by said support for pivoting said contact closer for rocking movement, stop means for limiting movement of said contact closer to contact closing and opening positions, a spring mounting pivotally and slidably mounted on said shaft, a spring acting between said mounting and contact closer and exerting pressure on said contact closer in a direction toward said shaft, disengageable positioning means acting between said mounting and support and disengageable upon axial movement of said mounting, said positioning means being adapted to hold said mounting in a position in which the spring exerts pressure in a dead center direction with reference to said shaft when said contact closer is in an intermediate position or in a position in which the spring urges the contact closer toward contact closing position regardless of the position of said contact closer or in a position in which the spring urges the contact closer toward contact opening position regardless of the position of the contact closer.

11. In a switch mechanism, a support, a rocking contact closer, a shaft carried by said support for pivoting said contact closer for rocking movement, stop means for limiting movement of said contact closer to contact closing and opening positions, a spring mounting pivotally and slidably mounted on said shaft, a spring acting between said mounting and contact closer and exerting pressure on said contact closer in a direction toward said shaft, a latch on said mounting, a positioning member on said support and having notches therein open for the endwise reception of said latch, said notches being spaced circumferentially and resilient means for urging said latch into said notches.

12. In a switch mechanism, a support, a rocking contact closer, a shaft carried by said support for pivoting said contact closer for rocking movement, stop means for limiting movement of said contact closer to contact closing and opening positions, a spring mounting pivotally and slidably mounted on said shaft, a spring acting between said mounting and contact closer and exerting pressure on said contact closer in a direction toward said shaft, a latch on said mounting, a flange on said support and extending parallel to the axis thereof, said flange having an end disposed in a diametral plane and formed with notches for the endwise reception of said latch, said notches being spaced circumferentially and locking means for holding said latch within any of said notches.

13. In a switch mechanism, a support, a rocking contact closer, a shaft carried by said support for pivoting said contact closer for rocking movement, stop means for limiting movement of said contact closer to contact closing and opening positions, a spring mounting pivotally and slidably mounted on said shaft, a spring acting between said mounting and contact closer and exerting pressure on said contact closer in a direction toward said shaft, a latch on said mounting, a flange on said support and extending parallel to the axis thereof, said flange having an end disposed in a diametral plane and formed with notches for the endwise reception of said latch, said notches being spaced circumferentially and locking means for holding said latch within any of said notches.

disposed in a diametral plane and formed with notches for the endwise reception of said latch, said notches being spaced circumferentially and a compression coil spring on said shaft and engaging said support and said mounting and urging said latch into said notches.

14. In a switch mechanism, a contact closer, movable from contact closing to contact opening position, an actuator for said contact closer, guide means for guiding said actuator for movement in opposite directions, said actuator when moved in one direction moving said contact closer into contact closing position and when moved in the opposite direction moving said contact closer into contact opening position, resilient means

15 for biasing said actuator for movement in either direction from an intermediate position, and a selector for varying the bias of said resilient means to cause movement of said actuator in either direction.

16. In a switch mechanism, a contact closer, movable from contact closing to contact opening position, an actuator for said contact closer, guide means for guiding said actuator for movement in opposite directions, said actuator when moved in one direction moving said contact closer into contact closing position and when moved in the opposite direction moving said contact closer into contact opening position, two opposed spring members acting on said actuator and moving said actuator to an intermediate position, and a selector for rendering either of said springs ineffective to transfer control of said actuator to the other spring.

17. In a switch mechanism, a contact closer, movable from contact closing to contact opening position, an actuator for said contact closer, guide means for guiding said actuator for movement in opposite directions, said actuator when moved in one direction moving said contact closer into contact closing position and when moved in the opposite direction moving said contact closer into contact opening position, two opposed spring members acting on said actuator and flexed to move said actuator to an intermediate position, and a selector acting on said springs and movable in opposite directions to further flex either of said springs and render either of said springs ineffective to transfer control of said actuator to the other spring.

18. In a switch mechanism, a contact closer, movable from contact closing to contact opening position, a spring for urging movement of said contact closer, a selector for shifting said spring to urge movement of said contact closer into one or the other of said positions, an actuator for

said contact closer guide means for guiding said actuator for movement in opposite directions said actuator when moved in one direction moving said contact closer into contact closing position and when moved in the opposite direction moving said contact closer into contact opening position, two opposed spring members acting on said actuator and moving said actuator to an intermediate position and means on said selector for rendering either of said last named springs ineffective upon the shifting of the first named spring.

19. In a switch mechanism, a support, a rocking contact closer, a shaft carried by said support for pivoting said contact closer for rocking movement, said contact closer being movable from a contact closing position to a contact opening position, an actuator movable relative to said contact closer and adapted to occupy two positions, said actuator upon actuation when in one position moving said contact closer into contact closing position and when in its other position upon actuation moving said contact closer into contact opening position, a selector mounted for swinging on said shaft and including a spring mounting, a spring acting between said mounting and contact closer and exerting pressure in a direction toward said shaft, said selector being movable to either of two extreme positions and when in one of said positions positioning said spring to urge movement of the contact closer into contact closing position and when in its other position positioning said spring to urge movement of said

5 contact closer into contact opening position, two opposed spring members acting on said actuator and moving said actuator to an intermediate position and means on said selector engageable with said last named springs and operable upon movement of said actuator to either of its positions to render one or the other of said last named springs ineffective.

10 20. In a switch mechanism, a contact closer, guide means for guiding said contact closer for movement to contact closing or contact opening position, a selector, guide means for guiding said selector for movement in a predetermined direction and for movement from one extreme position to another, a spring acting between said contact closer and selector and when the selector is in one extreme position urging said contact closer into contact closing position and when in its other extreme position urging said contact closer into contact opening position and locking means for holding said selector in either of said positions.

HOWARD W. ECKER.
